UNITED STATES PATENT OFFICE.

RICHARD MARCH SMITH, OF NORFOLK, VIRGINIA.

VALVE TESTER.

Application filed July 6, 1927. Serial No. 203,818.

This invention relates to valve testers, and more specifically to testers to be used in connection with inner tube valves.

The principal object of this invention is to provide means for indicating a leaky valve of the above description without resorting to the present unsanitary method of placing spittle on the valve.

Another object of this invention is to provide means for indicating leaky or faulty valves, by bubbles formed from a saponaceous material.

Further objects will be disclosed in the specification and drawings.

15 Referring to the drawings:

Figure 1 is an assembled side elevation of the tester;

Figure 2 is the same as Figure 1, with a section broken away;

20 Figure 3 is an end view of Figure 1.

In the drawings, similar parts are indicated by like numerals.

Numeral 1 designates a guard frame attached to an angularly shaped tube 2 on which 25 is mounted a bulb 3. The tube 2 is composed of a horizontal portion 4 and an elbow portion 5 which fits over the usual inner tube valve 6.

Within the tube portion 4 is placed a 30 saponaceous material 7 with a passage 8 leading into a chamber 9 which has an outlet 10 and an inlet 11. At the mouth of the inlet opening are rubber tips 12 for the purpose of making a snug contact when placed over an 35 inner tube valve. The chamber 9 is bell shaped so that its outermost edges form pockets 13 with the interior, convex and sloping upwardly until it reaches its highest point where the inlet passage 14 connects with 40 inlet opening 11.

As actually used, the saponaceous material is placed in the tube 2, the bulb 3 is deflated by pressing the same with the operator's hand, and the elbow 5 of tube 2 is submerged 45 in water and the bulb 3 allowed to fill by the release of the pressure exerted. The water in passing over this saponaceous material 7 becomes soapy and of such content that bubbles may very easily be formed.

50 In testing a valve, the rubber tip 12 is placed over lips of the valve, and the bulb 3 gently depressed. This forces the liquid over the saponaceous material through the small passageway 8 into the chamber 9. Be- 55 cause of the shape of this chamber, any sur-

plus liquid drains into the pocket 13, and prevents the same leaking into inlet passage 11, and at the same time, because of the convex surface presented, allows a thin film to form. This film may cover either or both of the 60 openings 10 and 14 without affecting the results. If the valve 6 is leaking, the escaping air will pass through the chamber 9 contacting with the film of saponaceous fluid opening 10, thus notifying the operator that the 65 valve leaks.

It is also apparent that the tester may be used effectively regardless of the position of the valve. If the tester is inverted from the position shown in the drawings, the film will 70 still form, and allow bubbles to indicate leaks.

What I claim is:

1. A tester for pneumatic valves comprising a soap chamber, a reservoir at one end of said soap chamber, a bubble chamber at the 75 other end of said soap chamber, and means providing a connection between the valves to be tested and said bubble chamber, said reservoir adapted to contain a liquid to be forced through said soap chamber into said bubble 80 chamber.

2. A tester for pneumatic valves, a liquid reservoir, a bubble chamber, said reservoir adapted to contain a liquid to be forced into said bubble chamber, means providing communication between the valves to be tested and said bubble chamber, said bubble chamber having an upper dome shaped wall and a convex bottom.

3. A tester for pneumatic valves comprising a soap chamber, a liquid reservoir at one end of said soap chamber, a bubble chamber at the other end of said soap chamber, means providing communication between the valves to be tested and said bubble chamber, said 90 bubble chamber having an upper dome shaped wall and a convex bottom, said reservoir adapted to contain a liquid to be forced through said soap chamber into said bubble chamber.

4. A tire tester for pneumatic valves comprising a body provided with a bubble chamber and means seatable on a valve, means for forcing a liquid into the bubble chamber, said body constructed to provide a passage 105 from the valve seat therein to the bubble chamber and there being an escape passage from said bubble chamber.

In testimony whereof I affix my signature.

RICHARD MARCH SMITH.
